EDWIN D. CHAPLIN, OF NEW YORK, N. Y.

IGNITION APPARATUS FOR GAS-ENGINES.

1,249,327.

Specification of Letters Patent. Patented Dec. 11, 1917.

Application filed January 27, 1916. Serial No. 74,531.

To all whom it may concern:

Be it known that I, EDWIN D. CHAPLIN, a citizen of the United States, residing in New York, in the county of New York and State of New York, have invented certain new and useful Improvements in Ignition Apparatus for Gas-Engines, of which the following is a specification.

This invention relates to ignition apparatus for gas engines, and has for a principal object to furnish space-proportioning means whereby the space within the ignition chamber of such engines may be regulated or adjusted with relation to the gas-igniting device.

A further object is to furnish an ignition apparatus or device of that class which shall have means for effecting such a regulation of two portions of the said chamber space in such a manner as to modify the form, or relative longitudinal and transverse dimensions, of one of said portions by reducing the capacity, or volume thereof while increasing the capacity or volume of the other said portion of the chamber space; also,—as regards that portion of a chamber-space which is intermediate to the cylinder of an engine and the igniting device,—to modify the transverse dimensions or area of such portion without a proportionate change in the length thereof.

A further object is to provide a displacer device so located and arranged that by changing the position thereof a storage-space for the spent and heated gas may be increased in capacity concurrently with a decrease of the transverse area, cross-section or capacity of a chamber-space forming a conduit between such storage-space and the cylinder of the engine, so that an increase in the capacity of said storage-space may be accompanied by a variation in the velocity or rate of the flowage of the gases through said conduit-space to and from said storage-space.

In the drawings accompanying and forming a part of this specification, Figure 1 is a plan view of an ignition device made in accordance with certain features of my present improvements, and the device is here shown with the upper portion of the casing broken away for more fully indicating the arrangement of certain interior details.

Fig. 2 is a side elevation drawn in alignment with Fig. 1, and the casing is shown broken away approximately on the line 2—2

Fig. 1, but without the displacer member being shown in section.

Fig. 3 is a view,—as seen from the left hand in Fig 2,—of the upper portion of the device in the form thereof shown in Figs. 1 and 2, a portion of the casing being broken away for more fully exhibiting one particular arrangement of the details.

Fig. 4 is a view similar to Fig. 2, and shows certain operative parts in a different position for thereby illustrating certain features of the operation of the device.

Fig. 5 is a view similar to Figs. 2 and 4 and illustrates a modified arrangement of the ignition device and the chamber therefor.

Fig. 6 is a view corresponding to Fig. 5 and is arranged for illustrating certain operational features as hereinafter more fully explained.

Fig. 7 is a view similar to Figs. 2, 4 and 5, but is arranged for illustrating certain modifications and supplemental features.

Fig. 7^a is a plan view of the mechanism when arranged as in Fig. 7, the upper portion of the casing being broken away for more clearly showing some of the details.

Fig. 8 is a sectional side elevation for illustrating a modification of certain of the details.

Fig. 9 is a side elevation arranged in a manner analogous to the construction shown in Figs. 5 and 8, but with a modified form of casing and a modified arrangement of the operable members of the ignition device.

Fig. 10 is a plan view of the ignition device in the form thereof illustrated in Fig. 9, the upper portion of the casing being broken away in a manner similar to the illustrations in Figs. 1 and 7^a.

Figs. 11 and 12 are views similar to Fig. 9, but showing the operating parts in different positions for thereby illustrating the purposes and mode of action thereof.

Similar characters designate like parts in all of the views.

In the drawings, for convenience of illustration, the several figures illustrating the different forms and specific arrangements of the ignition apparatus, are shown on a relatively large scale, while the fragmentary portion of the engine cylinder, D, is indicated on a comparatively small scale, but it will be understood that in practice the size and proportions, and the adjustments of the apparatus may be such as required,

- in any particular instance, in view of the size and proportions of the engine to which the apparatus is to be applied, and the speed of such an engine, and the character or richness of the gas mixtures which are employed therein. As usual in the gas-engine art, all such requirements are readily ascertainable by trial, and, besides, are to a considerable extent, matters of judgment or preference.
- 10 The casing or hollow framework, of the device is designated in a general way by C, and it may have any suitable form and proportions. In each of the Figs. 1 to 6 inclusive, the casing C is shown of a similar form and construction, and has an interior chamber space between flat side-walls, as 5^a, 5^b, (Figs. 1, 3), and one side wall, 5^b, is indicated as being removable; in practice, wall 5^b may be secured in place by suitable screws or rivets (not shown), but the particular manner of constructing the casing is not in itself important. The casing C may be removably secured to the cylinder D by means of a threaded stem, as S, and, preferably, may have a base-flange, or face, as f; in some instances, however, as indicated in Figs. 7, 7^a, the flange may be enlarged, as at f', and held in place by screws, s', so that the part s may be omitted.
- 30 The casing C is shown as having an interior chamber space within which is enclosed an operably-supported displacer member designated by B, in Figs. 1 to 6; by B¹ in Figs. 7, 7^a; by B², in Fig. 8; by B³, in Figs. 10 to 12. In each form, however, the displacer has, in some respects, the same functions and utility, and a similar mode of operation. Said chamber space is arranged for one part thereof, as 6^a, to serve 40 as a conduit space, while another part, 6^b, serves as a storage space. The lower part of the conduit 6^a, as at 6^c, may be regarded as a port which leads into the interior of the cylinder D.
- 45 In the form and arrangement of ignition apparatus particularly illustrated in Figs. 1 to 6, the working movements of the displacer member B take place in a diagonal direction, or at an incline relatively to the 50 direction of the conduit-space 6^a, and also operates as a port-adjuster. In said Figs. 2 to 6 the displacer B,—this being preferably of substantially a triangular form—is shown arranged for having working 55 movements in the direction of the inclined side thereof so that on moving the displacer downwardly for narrowing the conduit-space 6^a, (Fig. 4) the displacer also, operates as a port-adjuster. Thus the displacer when 60 arranged for operating in substantially such a manner as illustrated in Fig. 4, constitutes a combined space-proportioner and port-adjuster. In this manner, the operation of the said displacer-member B results 65 in simultaneously modifying or proportion-

ing the two spaces 6^a and 6^b which together form the inflaming-chamber, and concurrently with the described space regulation also regulates the size of the port-opening, 70 6^d, through which the incandescing-chamber, g, communicates with the inflaming-chamber.

In practice, the movement of the displacer B may be extended to a greater or lesser degree as may be required in any particular instance, and it is one of the objects of my improvement to provide for such an operation of the displacer as will in some cases serve to nearly or fully close, as the case may be, the port-opening 6^d when the 75 displacer is in the lower position thereof as indicated in Fig. 4. In this position, the displacer is shown nearly covering said port, so that for the time being the incandescing-chamber g will be substantially cut 80 off from communication with the inflaming-chamber 6^a. When the displacer B is in said lower position and the incandescing-chamber is cut off as described, it is evident that the compression-stroke of the piston by forcing the gases (usually a mixture of fresh and inert gases) through the relatively narrow conduit-space 6^a will drive the gases previously contained in the inflaming-chamber upward into the storage-space 90 6^b. During the further compression of a fresh charge in the cylinder of the engine, fresher gases will be supplied to and driven up through, under an increasing compression the said conduit-space 6^a and thus be 95 conducted to and beyond the port 6^d. If now during the later stages of the compression stroke, the displacer be rapidly drawn upwardly and thereby materially enlarge 100 the conduit-space 6^a, (Fig. 2) a largely increased volume of the fresher gases will be driven up through this conduit-space while the increasing compression will naturally hold the inert gases (previously in the 105 storage-space 6^b), confined in that chamber-space notwithstanding the upward movement of the displacer and the consequent reducing capacity of said storage-space. Said upward movement of the displacer whereby the conduit-space is largely increased in capacity, (as for instance, from 110 size Fig 4 to size Fig 2), operates as will now be evident, to uncover the port 6^d and thus at one and the same time provide for the sudden upflow of a larger volume of the 115 fresher and more highly compressed gas substantially at the moment of reestablishing or enlarging the communication between the incandescing-chamber g and the inflaming-chamber of the apparatus.

For operating the displacer B, in the manner above indicated, any suitable displacer actuating device, as for instance, the lever-device herein illustrated, may be connected with a suitable crank-pin or other actuator 125 13

on the engine. This means for mechanically and regularly actuating the displacer is diagrammatically indicated in Fig. 6, where 8 indicates a shaft which in practice should 5 have a rotation in synchronism with the cycle of movements of the engine. The circle 8^a indicates the path of a crank-pin 8^b, and 8^c indicates some suitable connecting rod or transmitter from said crank-pin to the lever- 10 arm 8^d of the displacer actuating device. Thus, the space-proportioning means herein described is adapted for synchronous operation with the piston of the engine to which the ignition apparatus may be applied and 15 is also adapted for operating as a combined space-proportioner and port-adjuster. The method of mechanically operating the displacer as here particularly described in connection with Fig. 6, may be applied, of 20 course, to any of the forms or arrangements of the displacers illustrated in the other figures of the drawings. Instead of using the crank-form of displacer-actuating device, the displacer may be operated by some 25 suitable cam, (not shown) provided with suitable connecting means, and located in a convenient position with relation to the ignition-apparatus.

For convenience of illustration and also 30 for indicating a preferred construction, the coil-form igniter N is shown in the detail views (see Fig. 1), arranged with the two leading wires e, e' thereof embedded in a plug or carrier member P which may be 35 formed in one piece of some suitable non-conducting material, such for instance as a suitable glass or asbestos composition, or of other appropriate dielectric substance. Said leading wires of the coil N are shown in Fig. 40 8, as having within the plug P, a slightly undulated form whereby they will be prevented from having any movement in the plug P should the wires for any reason be loosely embedded in the substance of the 45 plug. From the outer ends of said wires e, e', the usual electric conductors, (not shown) will be connected with a suitable supply of electricity for the purpose of heating the coil N to the proper degree of incandescence. In practice suitable switches 50 or the like (not shown) will, of course, be employed for turning on and turning off the electric current. The said leading wires e, e', may be non-incandescing, and may 55 then be joined by welding or in other suitable ways, to the opposite ends, respectively of the coil N, which will be so made as to be heated to incandescence by a suitable electric current, in a well-known manner. 60 The several coils or turns of the member N, constitute a kind of cage within which an increment of the gas-mixture will normally and for a moment be detained,—or reduced to a slow movement or circulation,—so that 65 this detained increment of the gas will be

more effectively heated than would otherwise be the case, and hence will be more uniformly heated in a given time-interval, and thus successive gas increments, or changes, be brought to the point of inflaming in successive time-intervals of a more uniform duration. In practice, the coil N, or some other gas-heating device or element in lieu thereof, may be made of such size and heating power as shall be required in any given 70 75 instance.

In Figs. 1 to 6, inclusive, the reversibly-operable displacer B, has the form of a sliding member which is in position and arranged for reciprocatory movements in directions for increasing and decreasing the cross-sectional area of the conduit-space, as 6^a, and thereby change the dimension or capacity of the conduit-space relatively to the capacity of the storage-space, as 6^b. In 80 each of the described arrangements or forms of the apparatus, the displacer member,—whether this is of a sliding construction or is otherwise formed,—is in position and arranged for working movements whereby to 85 effect the purposes and objects as above set forth. The required working movements of the said displacer may be effected by means of a shaft, as 9, which is provided with a crank pin, 9^a, and is so supported and arranged as to constitute a displacer-actuator. In said Figs. 1, 6 this displacer-actuating device consists of the described crank-shaft supported in some suitable bearing, and having the pin 9^a thereof in operative connection 90 with the displacer, which in the form shown in said Figs. 10, 12 is a rotatable member, B^a, having a central hole or bearing in which the crank pin engages. In Figs. 1 to 7^a, said crank pin is shown engaging in a slot 9^b of the sliding displacer, whereby the said crank shaft becomes a slide-actuating device that is in operative connection with the sliding-displacer, and is arranged for advancing and retracting the displacer for thereby 100 effecting the described regulation of the capacity of said storage-space and of the conduit-space, each relatively to the other.

A convenient and preferable mode of arranging the igniter-chamber g is well shown 115 in said Figs. 1 and 3, in which said space is located to one side of the conduit-chamber 6^a, and within an enlargement of the casing wall 5^a. In these views, the displacer-member B is shown so arranged as to partially 120 close in, or extend over said space g, for thereby coöperating with other features in providing for a more complete detention of an ignition charge of freshly compressed gas within said ignition chamber at the proper 125 moment. In this arrangement of the mechanism, the operating or shifting of the displacer for increasing or decreasing the cross-sectional area of the conduit-space, as 6^a, simultaneously increases or decreases the ex- 130

tent to which the igniter-chamber is covered in or separated from the conduit-space 6^a; thus, a single movement of the displacer, results in modifying the relations of three features, viz: increasing the storage-space 6^b, decreasing the conduit-space 6^a, and reducing the opening 6^d into the igniter-chamber *g*.

The igniter device, as *N*, being located 10 relatively remote from the main space of the cylinder, the chamber space 6^a leading from the port 6^c to the igniter, constitutes a conduit-space through which the fresh charge of gas,—during the compression- 15 stroke of the engine piston,—will flow to the igniter-chamber, with a velocity which, in practice, will depend on or be modified by the relative size of said conduit-space proportionately to the capacity of the stor- 20 age-space. Hence, by operating the displacer and thereby changing said proportionate relations, the velocity of the stream of gas through said conduit-space may be regulated, and the quantity of gas in the 25 storage space or chamber also be regulated. On the heating of the gas to an inflaming temperature in the igniter chamber *g*, the flame not only will then extend to and along the column of gas in the conduit-space, but 30 owing to rapid expansion of the gas by the inflaming thereof, the ignition-charge will naturally be rapidly forced out into the cylinder and thus more quickly inaugurate combustion in the main body of the com- 35 pressed gas. Thus the time-interval be- 40 tween the beginning of combustion in or at the ignition space, and the entrance of flame through the port 6^c into the cylinder, comprises the period of normal flame-travel as reduced by the movement of inflamed gas by flowage toward said port 6^c.

An immediate effect, when the engine is running, of the above described decrease of the conduit-space 6^a relatively to the ca- 45 pacity of the storage space 6^b, is obviously to accelerate during the compression stroke of the usual piston (as *d*, Fig. 9) the stream of gas through said conduit space into said storage space, and by this means it appears 50 that the residue of spent gas in these chamber spaces at the beginning of said stroke, will be more completely driven and compressed into the storage space, and thus bring a fresher mixture of the gas to the 55 igniter chamber *g*, and thereby effect the inflaming of the ignition charge at an earlier moment in the cycle of operations. Thus the operation of the displacer serves to regulate the timing of the ignition, and also to 60 regulate or modify the character of the gas mixture which has to be inflamed, and these two kinds of regulative action are effected concurrently by one movement of the displacer device, either to advance or retard the inflaming of the charge, accordingly as said 65

displacer-member shall be moved in one direction or the other, and accordingly as this operation shall be timed.

From the foregoing description, it will now be seen that one feature of my invention relates to an organization of chamber spaces in such a manner relatively to an igniting-device, and a chamber therefor, that a portion of freshly compressed gas may be subjected to a detentive control in contact with the igniter while relatively protected from the main stream during the flowage of gas toward the storage-space of the ignition-chamber. One arrangement and construction for this purpose is where the coil-form igniter is located within a small auxiliary or igniter chamber, *g*, which is located at one side of but in communication with the conduit-space. This arrangement allows a stream of gas to flow rapidly through said conduit-space, while holding some gas,—under a less violent motion or flow,—within the space *g* and in direct engagement with the incandescent igniter. A further feature of this arrangement relates to the use in such an organization of a special form of incandescent igniter located in said space or igniter-chamber *g*, so that a small amount of gas will flow or circulate within such chamber in contact with several turns of the coil-form igniter, and thus be rapidly brought to the temperature of or to the state of, combustion. When this result is effected, the flame or combustion then proceeds outward from the igniter, and passing through the conduit-space quickly reaches the cylinder space, and so accomplishes the inflaming of the main body of gas within the cylinder.

The inflaming-chamber in each of the constructions illustrated, being of an elongated form, and at or near one end thereof being in communication with the cylinder *D*, therefore when no gas-mixture is initially supplied to the cylinder through said chamber, it follows that on the engine piston (as *d*, Fig. 9) coming to the end of its compression stroke the gas in said chamber will come substantially to rest, and thus be in a highly favorable condition for the inflaming thereof. One object of my invention, however, is to secure a high degree of efficiency of the inflaming action without requiring the ignition-charge to be brought fully to rest, and for this purpose among others, I preferably locate and arrange the igniter or heating device, as *N*, in an auxiliary chamber, as *g*, which is a comparatively separate space, although communicating with the inflaming chamber at a point preferably located approximately midway of the length thereof.

By the term approximately midway of the length of the inflaming-chamber, as herein employed in defining certain features comprised in or related to my present improvements, I refer to such a location of the igni- 130

ter at a point along the length of the heating or inflaming-chamber, as will effect the apportioning of the space within this chamber into a conduit-space extending from the igniter to the cylinder of the engine and a storage-space located beyond the igniter and in position for receiving the inert gases from the conduit-space during the compression-stroke of the piston of the engine. In some instances, as illustrated for instance in Fig. 2, the storage-space, or chamber, as 6^b may be diametrically enlarged or otherwise proportioned so as to have a relatively short length in combination with a diametrical enlargement which thus becomes an equivalent for a relatively longer storage-space or chamber of a relatively smaller diameter. In practice, it is only required that the storage-space shall have a substantial amount of space therein so that during said compression-stroke, some of the gases which would otherwise remain adjacent or contiguous to the igniter will be pushed along by the inflow of the fresh gas then being compressed as this gas passes from the cylinder through the said conduit space, as 6^a, to the immediate vicinity of the igniter.

In Figs. 7 and 7^a, I have illustrated a modification as regards the arrangement and specific features of the operably-supported space proportioning displacer member, here designated by B¹. In these views, the displacer member is shown pivotally supported within the casing C¹ by a pin at t. A slot 9^b is formed in the displacer for receiving the crank-pin 9^a of the lever-device mechanism, which as here shown, or may be substantially a duplicate of the one illustrated in Figs. 1 to 6, inclusive; and accordingly the minor details of this displacer-actuating means are here designated by the same reference characters, respectively, as in the preceding views showing the same details. In this modification the igniter chamber 9, is formed within a projecting part of the casing, and communicates through a port at 6^a with the conduit portion 6^a of the inflaming-chamber. The conduit-space 6^a and the storage-space 6^b, (Fig. 7) are modified in proportion by a swinging movement of the displacer B¹ produced (as in Fig. 2) by simply turning the crank. It will be evident that when the displacer B¹ is moved toward the left hand in Fig. 7 so as to narrow the conduit-space 6^a then said storage-space will be increased in size and capacity by relatively the same amount. As in the other forms of the apparatus, as herein described, in connection with other figures of the drawing, the igniter-chamber is so located as to be substantially separate from the inflaming-chamber which comprises the said conduit-space and the storage-space.

In the several views, Figs. 1 to 7^a, the arrangement of the operably-supported dis-

placer is such that the conduit-space is decreased concurrently with an increase of the storage-space, and by the same working movement of the displacer. In Fig. 9, I have illustrated a modification of the ignition apparatus in which a displacer B² is operably supported for a sliding movement in a direction substantially at right angles to the sliding movement of the displacer B¹ in Fig. 2. In this modified arrangement, (Fig. 9), a movement of the displacer B² toward the igniter chamber, operates to reduce the capacity of the conduit-space 6^a and also the storage-space 6^b at the same time. However, a single reciprocating movement of the displacer B² operates in a direction for decreasing the capacity of both of said spaces 6^a, 6^b, and does this in a different proportion. Thus a given movement of the displacer operates a space-proportioning means. For operating the said modified arrangement of the displacer, I have shown said displacer connected by a rod h to the end of the lever h² at the point h³. The lever is shown pivotally supported at h⁴, to some part of the flame or casing C² of the apparatus. In practice, however, the said displacer may be operated by means of a lever device having the crank-shaft arrangement such as already described in connection with Fig. 6, as will be readily understood without further description.

In a further modification illustrated in Figs. 10 to 12, inclusive, the reversibly-operable displacer member B³ is illustrated as being arranged within the casing C³ and for a working movement in directions which is concentric relatively to the shaft 9, for thereby increasing and decreasing the cross-sectional area of the conduit-space 6^a, and thereby change the capacity (as regards the flowage of gas therein) of this conduit-space relatively to the capacity of the storage-space, as 6^b. This displacer B³ is shown of a circular form, or disk, revolvably supported on the crank 9^a, so that by turning said shaft 9, the displacer may be shifted to successive positions, of which three are shown in Figs. 9, 11 and 12, respectively; by comparing these views, the operation of the member B³ for changing the relative proportions of the said conduit and storage spaces, will be obvious. The improvements illustrated in Figs. 10 to 12, and which are not also comprised in the devices of the preceding figures are not specifically claimed herein, but will constitute in part the subject-matter of a separate application to be copending herewith.

For operating the shaft 9, and for holding the same in different positions, there is provided a retractable locking device of a well-known kind, indicated at 8^r and arranged to engage in holes, 8^t, in the flange, or "quadrant" of the casing or frame of the appa-

tus. See Figs. 7, 7^a and 9, 10. This or some like arrangement may be applied to the shaft 9 of any form of the apparatus, whenever it is not required to operate the displacer as described in connection with Fig. 6, but only to adjust the position of the displacer from time to time.

In the drawings, the conduit-space, as 6^a Figs. 1-6, or 6^b, Figs. 7, 8, leads in one direction from the igniter, or from the port of the igniter-chamber, to an outlet, as 6^c, for communicating with the cylinder of the engine; while in an opposite direction (or in another direction) the conduit-space has a continuation thereof (of some suitable form and arrangement) which constitutes a storage-space, in the manner and for the purpose already pointed out.

By locating the incandescing chamber, 20 (as *g*, Figs. 1, 2), out of line with the said conduit channel or space, the gas within said chamber is less disturbed than it otherwise might be, during the compression stroke; and by locating and arranging the 25 inflaming-chamber without any connection with the gas-supply apparatus of the engine, disturbances from that source are also avoided.

Referring to Figs. 1 and 3, I have indicated at *n* a lining within the incandescing chamber *g*. This lining should be of relatively high non-conducting quality for thereby aiding in the rapid heating of the gas in said chamber up to a temperature 35 whereby it may communicate flame through the port or outlet thereof to the gases in the conduit-space of the inflaming-chamber. In practice, such a lining may consist of an inserted layer or member, and this consist of 40 some suitable variety of glass or relatively infusible material which may, if preferred, be fused or welded onto the inner surface of the casing; and in some cases this non-conducting lining may be extended over 45 other interior portions of the casing; also, it may be so applied within any form of the casing or of the incandescing-chamber.

It should be noted in connection with the several specific arrangements of the inflaming-chamber and the igniter, and also as regards the igniter-chamber considered as an incandescing-chamber, that normally this chamber may ordinarily be filled with relatively inert gas so that the charge of gas 55 in said incandescing-chamber may be heated to the point of incandescence without establishing combustion therein. This is especially to be noted in connection with such a construction of the apparatus as substantially separates the incandescing-chamber 60 from the inflaming-chamber and particularly when in this latter arrangement, the communication is through a port having means whereby the same may be nearly or 65 entirely closed. In the latter case, the

charge of inert gas contained in the incandescing-chamber may be heated up to a point beyond that which is required for combustion in a charge of fresh gas, so that on the reestablishing of communication in said two chambers,—or on bringing the fresh gas in sufficient volume through the conduit-space to the igniter,—the incandescing, but non-burning gas by mingling with the fresh gas causes combustion to take place therein, and by the aid of the flowage and the expansion already described this combustion is rapidly communicated to the main charge in the cylinder. Thus by the use,—and the arrangements set forth,—of the incandescing igniter in connection with a space-proportioning means, the combustion may be established and communicated without requiring combustible gas to be in actual contact with the igniter.

By arranging the operating devices suitably therefor, as elsewhere herein explained as regards an operating mechanism such as indicated in Fig. 6, the displacer member (whatever the specific form thereof) may be so arranged and operated that on the completion of the compression stroke of the engine, the displacer may be actuated in a direction for expelling heated gas from the storage portion of the chamber; and, when the chamber and conduit spaces as 6^b and 6^a are suitably proportioned therefor, the heated contents of the storage space may be forcibly expelled in the form of a jet into the cylinder of the engine, so that the heated 95 gases thus injected into the cylinder space will operate by their own heat, as an ignition means, and this without requiring such injected gases to be in a burning or a flaming condition. The arrangements may be so proportioned and the displacer member 100 so timed in its operation as to effect the said expulsion of heated ignition-gas concurrently with the enlargement of the conduit-space contiguous to the cylinder space, and thereby permit "live-gas" from the cylinder to flow up into the conduit-space concurrently with the said expulsion of ignition-gas from the chamber-space, and by this means, it will now be evident, the ignitable gases from the cylinder may flow into the conduit-space concurrently with the ejection of heated gas from the storage-space 110 and thus cause the initial firing or ignition of the said live gas to take place at a point in the conduit-space rather than within the cylinder space itself. And under some conditions, or when the actuated devices are suitably arranged therefor, the firing of the charge may be thus accomplished by the 115 heat of the confined gases without the live-gas coming into actual contact with the heating element of the ignition apparatus, since the confined gas may be so highly heated as to cause the inflaming of the cyl- 120 125 130

inder charge by the heat of said ignition-gas after this is in a fully burned or inert condition and therefore not itself inflammable.

5 Having thus described my invention, I claim:

1. In ignition apparatus for gas engines, in combination, a casing, an igniter within the casing, an inflaming-chamber consisting

10 of a conduit-space leading in one direction from the igniter to an outlet for communicating with the cylinder of the engine, and having in an opposite direction a continuation thereof constituting a storage-space, and 15 space-proportioning means in a position intermediate to said igniter and outlet and arranged for increasing and decreasing one said space relatively to the other said space of the inflaming chamber.

20 2. In ignition apparatus for gas engines, in combination, a casing, an incandescing igniter within the casing, an inflaming-chamber consisting of a conduit-space leading in one direction from the igniter to an 25 outlet for communicating with the cylinder of the engine, and having in another direction a continuation thereof constituting a storage-space, and space-proportioning means in a position intermediate to said 30 igniter and outlet and arranged for increasing and decreasing one said space relatively to the other said space of the inflaming-chamber.

3. In ignition apparatus for gas engines, 35 in combination, a casing, an igniter within the casing, an inflaming-chamber consisting of a conduit-space leading from the igniter to an outlet for communicating with the cylinder of the engine, and having a continuation 40 thereof constituting a storage-space, and space-proportioning means in position and arranged for increasing the capacity of one said space and simultaneously decreasing the capacity of the other said 45 space of the inflaming-chamber.

4. In ignition apparatus for gas engines, 50 in combination, a casing, an igniter-chamber within the casing and an incandescing igniter within the igniter-chamber, an inflaming-chamber in communication with the igniter-chamber and consisting of a conduit-space leading from the igniter to an outlet for communicating with the cylinder of the engine, and having a continuation thereof constituting a storage-space, and space-proportioning means in position and arranged for increasing the capacity of one said space and simultaneously decreasing the capacity of the other said space of the inflaming-chamber.

5. In ignition apparatus for gas engines, 55 in combination, a casing, an igniter-chamber within the casing and an igniter within the igniter-chamber, an inflaming-chamber in communication with the igniter-chamber

and consisting of a conduit-space leading from the igniter to an outlet for communicating with the cylinder of the engine, and having a continuation thereof constituting a storage-space, and space-proportioning 70 means in position and arranged for increasing the capacity of one said space and simultaneously decreasing the proportionate capacity of the other said space of the inflaming-chamber.

6. In ignition apparatus for gas engines, in combination, a casing, an igniter-chamber within the casing and an igniter within the igniter-chamber, an inflaming-chamber in communication with the igniter-chamber 80 and consisting of a conduit-space leading from the igniter to an outlet for communicating with the cylinder of the engine, and having a continuation thereof constituting a storage-space, and space-proportioning 85 means comprising a sliding displacer in position and arranged for increasing the capacity of the conduit-space and simultaneously decreasing the proportionate capacity of said storage-space.

7. In ignition apparatus for gas engines, the combination with an inflaming-chamber comprising a conduit-space having a continuation thereof constituting a storage-space, of an incandescing chamber adjacent to the 95 junction of the conduit-space and the storage-space and in communication with the inflaming-chamber, an igniter located within said incandescing chamber, space-proportioning means comprising an operably-supported displacer, and displacer-actuating means in position and operatively connected for operating the displacer.

8. In ignition apparatus for gas engines, the combination with an inflaming-chamber 100 comprising a conduit-space having a continuation thereof constituting a storage-space, of an incandescing chamber adjacent to the junction of the conduit-space and the storage-space and in communication with the 105 inflaming-chamber, an igniter located within said incandescing chamber, space-proportioning means comprising a sliding displacer, and displacer-actuating means in position and operatively connected for sliding 110 the displacer.

9. In ignition apparatus for gas engines, the combination with an elongated inflaming-chamber, of an inclosed igniter located approximately midway of the length of the 115 inflaming-chamber and thereby apportioning the space within this chamber into a conduit-space and a storage-space, and a reversibly-operable displacer-member in position and arranged for working movements 120 in direction for increasing and decreasing the cross-sectional area of said conduit-space and thereby change the capacity of the conduit-space relatively to the capacity of the storage-space.

10. In ignition apparatus for gas engines, the combination with an elongated inflaming-chamber, of an inclosed igniter located approximately midway of the length of the 5 inflaming-chamber and thereby apportioning the space within this chamber into a conduit-space and a storage-space, and a reversibly-operable displacer-member in position and arranged for working movements 10 in directions for increasing and decreasing said storage-space and thereby change the capacity of the storage-space relatively to the cross-sectional area of the conduit-space.

11. In ignition apparatus for gas engines, 15 the combination with an elongated inflaming-chamber, of an igniter located approximately midway of the length of the inflaming-chamber and thereby apportioning the space within this chamber into a conduit-space and a storage-space, a displacer member in position and arranged for working movements in directions for simultaneously increasing one said space and decreasing the other said space, and thereby regulate the 20 cross-sectional area and capacity of the conduit-space and the capacity of the storage-space, each relatively to the other.

12. In ignition apparatus for gas engines, the combination with an elongated inflaming-chamber, of an inclosed igniter located approximately midway of the length of the inflaming-chamber and thereby apportioning the space within this chamber into a conduit-space and a storage-space, a reversibly-operable displacer-member in position and arranged for working movements in directions for increasing and decreasing the cross-sectional area of said conduit-space and thereby change and regulate the capacity 30 of the conduit-space relatively to the capacity of the storage-space, and a displacer-actuating device in operative connection with the displacer, and arranged for advancing and retracting the displacer and for 35 thereby effecting the said regulation of the capacity of said storage-space relatively to the conduit-space.

13. In ignition apparatus for gas engines, the combination with an elongated inflaming-chamber, of an igniter located approximately midway of the length of the inflaming-chamber and thereby apportioning the space within this chamber into a conduit-space and a storage-space, a reversibly-operable displacer-member in position and arranged for working movements in directions for increasing and decreasing said storage-space and thereby change and regulate the capacity of the storage-space relatively to 50 the cross-sectional area of the conduit-space, and a displacer-actuating device in operative connection with the displacer, and arranged for advancing and retracting the displacer and for thereby effecting the said

regulation of said conduit-space relatively 65 to the capacity of the storage-space.

14. In ignition apparatus for gas engines, the combination with an elongated inflaming-chamber, of an igniter located approximately midway of the length of the inflam- 70 ing-chamber and thereby apportioning the space within this chamber into a conduit-space and a storage-space, a reversibly-operable displacer-member in position and arranged for working movements in direc- 75 tions for simultaneously increasing one said space and decreasing the other said space, and thereby change and regulate the cross-sectional area and capacity of the conduit-space relatively to the capacity of the stor- 80 age-space, and a displacer-actuating device in operative connection with the displacer, and arranged for advancing and retracting the displacer and for thereby effecting the said regulation of the capacity of said stor- 85 age-space and the conduit-space, each relatively to the other.

15. In ignition apparatus for gas engines, the combination with an elongated inflaming-chamber, of an igniter located approxi- 90 mately midway of the length of the inflaming-chamber and thereby apportioning the space within this chamber into a conduit-space and a storage-space, and a reversibly-operable sliding displacer-member in position and arranged for working movements 95 in directions for increasing and decreasing the cross-sectional area of said conduit-space and thereby change the capacity of the conduit-space relatively to the capacity of the 100 storage-space.

16. In ignition apparatus for gas engines, the combination with an elongated inflaming-chamber of an inclosed igniter located approximately midway of the length of the inflaming-chamber and thereby apportioning the space within this chamber into a conduit-space and a storage-space, and a reversibly-operable sliding displacer-member in position and arranged for working movements 105 in directions for increasing and decreasing said storage-space and thereby change the capacity of the storage-space relatively to the cross-sectional area of the conduit-space.

17. In ignition apparatus for gas engines, the combination with an elongated inflaming-chamber, of an igniter located approximately midway of the length of the inflaming-chamber and thereby apportioning the space within this chamber into a conduit-space and a storage-space, and a sliding displacer-member in position and arranged for working movements in directions for simultaneously increasing one and decreasing the other of said spaces, and thereby change and regulate both the cross-sectional area of the conduit-space and the capacity of the stor- 110 age-space, each relatively to the other.

18. In ignition apparatus for gas engines, the combination with an elongated inflaming-chamber, of an igniter located approximately midway of the length of the inflaming-chamber and thereby apportioning the space within this chamber into a conduit-space and a storage-space, a reversibly-operable sliding displacer consisting of a sliding member in position and arranged for working movements in directions for increasing and decreasing the cross-sectional area of said conduit-space and thereby change and regulate the capacity of the conduit-space relatively to the capacity of the storage-space, and a displacer-actuator consisting of a slide-actuating device in operative connection with the sliding displacer, and arranged for advancing and retracting the displacer and for thereby effecting the said regulation of the capacity of said storage-space relatively to the conduit-space. 60
19. In ignition apparatus for gas engines, the combination with an elongated inflaming-chamber, of an igniter located approximately midway of the length of the inflaming-chamber and thereby apportioning the space within this chamber into a conduit-space and a storage-space, a reversibly-operable sliding displacer consisting of a sliding member in position and arranged for working movements in directions for increasing and decreasing said storage-space and thereby change and regulate the capacity of the storage-space relatively to the cross-sectional area of the conduit-space, and a displacer-actuator consisting of a slide-actuating device in operative connection with the sliding displacer, and arranged for advancing and retracting the displacer and for thereby effecting the said regulation of said conduit-space relatively to the capacity of the storage-space. 80
20. In ignition apparatus for gas engines, the combination with an elongated inflaming-chamber, of an igniter located approximately midway of the length of the inflaming-chamber and thereby apportioning the space within this chamber into a conduit-space and a storage-space, a reversibly-operable sliding displacer consisting of a sliding member in position and arranged for working movements in directions for simultaneously increasing one said space and decreasing the other said space of the inflaming chamber, and thereby regulate the capacity of the conduit-space and the capacity of the storage-space, each relatively to the other. 85
21. In ignition apparatus for gas engines, the combination with an elongated inflaming-chamber comprising a conduit-space having a continuation thereof constituting a storage-space, of an auxiliary incandescent chamber located contiguous to the junction of the conduit-space and the storage-space and in communication with the inflaming-chamber, an igniter located within said incandescent chamber, and space-proportioning means in a position intermediate to said igniter and outlet and arranged for increasing and decreasing the said storage-space of the inflaming-chamber, and thereby regulate the capacity of the storage-space relatively to the conduit-space. 90
22. In ignition apparatus for gas engines, the combination with an elongated inflaming-chamber comprising a conduit-space having a continuation thereof constituting a storage-space, of an auxiliary incandescent chamber located contiguous to the junction of the conduit-space and the storage-space and in communication with the inflaming chamber, an igniter located within said incandescent chamber, and space-proportioning means in position and arranged for simultaneously increasing one said space and decreasing the other said space of the inflaming chamber, and thereby regulate the capacity of the conduit-space and the capacity of the storage-space, each relatively to the other. 95
23. In ignition apparatus for gas engines, the combination with an elongated inflaming-chamber comprising a conduit-space having a continuation thereof constituting a storage-space, of a separate incandescent chamber having a port communicating with the inflaming-chamber at a point near the junction of the conduit-space and storage-space thereof, an igniter located within said incandescent chamber, and space-proportioning means in position and arranged for increasing and decreasing one said space relatively to the other said space of the inflaming chamber. 100
24. In ignition apparatus for gas engines, the combination with an inflaming-chamber comprising a conduit-space having a continuation thereof constituting a storage-space, of a separate incandescent chamber having a port communicating with the inflaming-chamber at a point near the junction of the conduit-space and storage-space thereof, an igniter located within said incandescent chamber, and space-proportioning means in position and arranged for increasing and decreasing one said space relatively to the other said space of the inflaming chamber and also arranged for concurrently changing the extent of the opening of said port into the inflaming-chamber. 110
25. In ignition apparatus for gas engines, 115
- 120
- 125

the combination with an inflaming-chamber comprising a conduit-space having a continuation thereof constituting a storage-space, of an incandescing chamber adjacent to the junction of the conduit-space and the storage-space and in communication with the inflaming-chamber, an igniter located within said incandescing chamber, and storage-space and conduit-space proportioning means comprising an operably-supported displacer, and also comprising a displacer-actuator consisting of a lever-device comprising a crank-shaft having a displacer-engaging crank-pin, said shaft being provided with operating means located in position outside of the casing of the ignition apparatus, whereby the displacer may be operated during the operation of the engine.

26. In ignition apparatus for gas engines, the combination with an inflaming-chamber comprising a conduit-space having a continuation thereof constituting a storage-space, of an incandescing chamber adjacent to the junction of the conduit-space and the storage-space and in communication with the inflaming-chamber, an igniter located within said incandescing chamber, and storage-space and conduit-space proportioning means comprising a slidably-supported displacer, and also comprising a displacer-sliding means consisting of a lever-device comprising a crank-shaft having a displacer-engaging crank-pin, said shaft being provided with operating means located in position outside of the casing of the ignition apparatus, whereby the displacer may be operated by a sliding movement during the operation of the engine.

27. In ignition apparatus for gas engines, the combination with an inflaming-chamber comprising a conduit-space having a continuation thereof constituting a storage-space, of an incandescing chamber adjacent to the junction of the conduit-space and the storage-space and in communication through a port-opening with the inflaming-chamber, an igniter located within said incandescing chamber, and storage-space and conduit-space proportioning means comprising an operably-supported displacer having a sliding movement, and also comprising a displacer-actuating lever-device provided with operating means located in position outside of the casing of the ignition apparatus, for sliding the displacer during the operation of the engine.

28. In ignition apparatus for gas engines, the combination with an inflaming-chamber comprising a conduit-space having a continuation thereof constituting a storage-space, of an igniter in a position adjacent to and in communication with the inflaming-chamber, space-proportioning means comprising an operably-supported displacer ar-

ranged for varying the relative proportions of the conduit-space and storage-space, a displacer-actuator comprising a displacer-engaging lever-device and having lever-device-operating means in position and arranged for operating the displacer-actuator and thereby operate the displacer during the operation of the engine, and actuator holding means located in position outside the casing of the ignition apparatus, and arranged for releasably holding the displacer-actuator and thereby hold the displacer in any one of several successive positions.

29. In ignition apparatus for gas engines, the combination with an inflaming-chamber comprising a conduit-space having a continuation thereof constituting a storage-space, of an igniter in a position adjacent to and in communication with the inflaming-chamber, space - proportioning means comprising a slidably-supported displacer arranged for varying the relative proportions of the conduit-space and storage-space, a displacer-actuator comprising a displacer-engaging lever-device and having lever-device-operating means in position and arranged for operating the displacer-actuator and thereby sliding the displacer during the operation of the engine, and lever-device locking means located in position outside the casing of the ignition apparatus, and arranged for releasably - locking the displacer-actuator and thereby also hold the displacer in any one of several successive positions.

30. In ignition apparatus for gas engines, the combination with a cylinder, and with a casing having therein a chamber in communication with the cylinder through a port of an incandescent igniter located in a mid-way portion of the length of the chamber and thereby apportioning the chamber space into a conduit space and a storage space, a movable displacer - member operably - supported within the casing and constituting a combined space-proportioner and chamber-port-adjuster, and an actuator device in position and arranged for operating the displacer-member.

31. In ignition apparatus for gas engines, the combination with an elongated inflaming-chamber, of an igniter located approximately midway of the length of the inflaming-chamber and thereby apportioning the chamber space into a conduit-space and a storage-space, said conduit-space being intermediate to the igniter and the cylinder of a gas engine, and a reciprocatable displacer-member in position and arranged for working strokes in directions for alternately increasing and decreasing the cross-sectional area of said conduit - space and thereby change and regulate the capacity of the conduit-space relatively to the ca-

pacity of the storage-space, and means for reciprocating said displacer-member.

32. In ignition apparatus for gas engines, the combination with a combined conduit and inflaming-chamber, of an igniter located in a space at a midway portion of the inflaming-chamber and thereby apportioning the chamber space into a conduit-space and a storage-space, said conduit-space being intermediate to the igniter and the cylinder of the gas engine, and an operably-supported displacer - member in position and
- 5 arranged for working strokes in directions for alternately increasing and decreasing the capacity of said conduit-space and thereby 15 regulate the capacity of the conduit-space relatively to the capacity of the storage-space, and means for operating the displacer-member.

EDWIN D. CHAPLIN.
